UNITED STATES PATENT OFFICE.

JOSEPH F. BARTOSH, OF WEIMAR, TEXAS, ASSIGNOR OF ONE-HALF TO FRANK KAHLIK, OF WEIMAR, TEXAS.

FILING CABINET FOR PRESCRIPTIONS, ETC.

Application filed June 23, 1925. Serial No. 39,045.

This invention relates to filing cabinets for prescriptions, records or other papers.

The object is to provide a simple, cheaply manufactured and strong and durable cabinet in the form of a box-like structure for holding a plurality of papers or records, preferably of uniform size, said cabinet being adapted to be used singly or alone or in connection with other similar cabinets to contain, each, a certain number of such papers, say an alphabetical division or a numerical section, taken, as desired, from the consecutive numbers of prescriptions, the boxes being so constructed as to permit of stacking one upon the other and in rows, the locking and withdrawing means being located at the front, as well as indicating means designating the contents.

Another object is to provide a cabinet in which, when the lid or cover is thrown back, the entire stack of filed prescriptions or papers is exposed on all sides and may be readily lifted or swung to one side to facilitate the thorough inspection of any one of said papers without removing the same from the filing means.

A final object is to provide a cabinet in which the papers are all maintained in substantial alinement with each other and which may be readily placed on or removed from the filing means when desired, the cabinet fully protecting said papers from fire, water or other damage.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

50 Figure 1 is a perspective view of the improved cabinet in closed position.

Figure 2 is a similar view in open position.

Figure 3 is a detail, vertical section illustrating the manner of mounting the filing means on the base of the cabinet.

Referring to the drawing and more particularly Figure 2 thereof, there is shown a filing cabinet constructed in accordance with the invention and comprising a flat, rectangular base member 1 formed of suitable, thin metal, such as sheet iron, or the same may be formed of ordinary commercial tin of heavy grade. The base 1 is preferably oblong in shape and is provided along its two long sides with upturned marginal flanges 2 formed by bending the metal upwardly, and along the front edge with a similarly formed flange 3, while the rear, narrow edge is provided with a plurality of integrally formed hinge eyes 4.

The front marginal flange 3 is provided with a centrally located, upstanding tongue 5 preferably formed by an integral extension thereof and provided adjacent to its upper end with an aperture 6, the terminal of the said tongue being turned forwardly and downwardly to constitute a loop-shaped finger-hold 7 for a purpose to be explained.

Adjacent to the rear end of the base member and at the longitudinal center line thereof, there is provided an elevated or struck-up portion 8, as clearly shown in Figure 3 of the drawing, formed by bending the sheet metal preferably in a circular form, thus providing a recess 9 beneath the base member, and said elevated portion is provided with a central aperture 10 into which there is seated the reduced end of a filing pin or post 11. The shoulder produced by reducing the lower end of the post is held in rigid connection with the upper face of the elevated portion 80 by a nut 12 located within the recess 9 so that the base member may rest flat upon any supporting surface without rocking.

The filing post is thus rigidly mounted on the base, and said post is threaded at its upper extremity for the reception of a suitable thumb nut 13 which may be easily and quickly removed for the purpose of applying or removing prescription blanks, cards or other records 14, which are preferably of a uniform, rectangular form somewhat smaller than the dimensions of the base, and which are preferably provided with apertures or punch holes 15 adjacent to one end and at the longitudinal center lines of said blanks. Thus when a stack of such records are filed upon the post, the same may be easily placed in alinement with each other and in spaced relation to the sides and ends of the base member. The nut 13 may, if desired, be dispensed with and the 105

filling post 11 provided with a pointed upper end for puncturing ordinary blanks or papers, as will be readily understood.

A hinged lid or cover of box-like formation 5 is adapted to be used in connection with the base, and said cover is likewise formed of the same kind of sheet metal as the base. The cover comprises a top 16 having longitudinal side walls 17 formed integrally therewith and 10 adapted to fit down within the aforesaid side flanges 2 of the base member when the cover is in closed position, as shown in Figure 1 of the drawing.

The top wall 16 and side walls 17 are provided at their front and rear ends with continuous, abutting flanges 18 turned inwardly and adapted to receive within the same a front wall 19 and a back wall 20 respectively, the lower edges of which are flush with the 20 lower edges of the side walls, and the margins of which may be secured within said flanges by soldering, welding, crimping or riveting, as desired.

The rear wall 20, at the free lower edge 25 thereof, is provided with complementary hinge eyes 21 adapted to fit between the aforesaid eyes 4 of the base member and to be pivoted thereto by a suitable hinge pin 22, which permits the cover to be swung forwardly and downwardly to rest directly upon the upper face of the base member, with the front and sides located within their respective flanges 2 and 3. When the cover is thus closed the aperture 6 in the aforesaid tongue is 35 adapted to receive a projection 23 formed on the front face of the front wall 19, such projection causing the tongue, which is sufficiently resilient, to spring forward slightly to allow such automatic locking engagement.

The front wall 19 is also provided with a suitable holding means 24 for receiving and holding an index card 25 having suitable indicia or information regarding the contents of the cabinet printed or written thereon, and 45 in addition thereto, the front wall is further provided with a small knob 26 which may be grasped for sliding the cabinet from a shelf or from beneath other like cabinets, when used in conjunction therewith.

From the foregoing it will be seen that a simple, strong and durable cabinet has been provided which is capable of holding in position a plurality of prescriptions or other papers to preserve the same in good condition, the cover of which may be quickly and 55 easily thrown back, uncovering the entire stack of papers so that the same may be readily turned to one side or the other, or elevated on the filing post, in a manner to expose any desired paper without removing the same from said post, and that, by merely removing the nut 13, other prescriptions, etc., 60 may be added from time to time. The cover when swung down and automatically locked

serves to protect the contents from accidental 65 injury or damage from fire or water.

What is claimed is:—

1. A filing cabinet comprising a flat base member having upstanding, marginal flanges along the front and side edges thereof, a 70 locking tongue integral with one of said flanges, an upstanding post mounted on the rear of the base for holding and alining prescriptions or the like, a box-like cover having a top wall and front, rear and side walls joined thereto, the rear wall being hinged along its free edge to the rear edge of the base, one of said walls presenting locking means cooperating with said locking tongue and the free edges of the front and side walls 75 fitting within the said flanges when the cover is lowered.

2. A filing cabinet comprising a sheet metal base provided along its front and side edges with upstanding flanges, the front flange having a spring hook, the rear edge of the base being formed into hinge elements, a sheet-metal-cover box having a top wall substantially equal in area to the base, and depending front, rear and side walls joined thereto, the front and side walls being adapted to fit, along their free edges, within the flanges of the base, said rear wall having complementary hinge elements at its free edge for connection to the elements on the base, said front wall having a projection for coaction with said spring hook and also having an index card holder, and means mounted on the base for holding and alining prescriptions or the like. 100

3. In a filing cabinet; a flat base adapted to support a stack of blanks; low, upstanding flanges formed on the front and side edges of the base and normally exposing said stack on the top and four sides thereof; a box-like cover adapted to fit on the margins of the base and completely cover the stack of blanks when closed, with the free edges of the front and side walls of the cover fitting within said flanges; coacting hinge elements formed on the free edge of the rear wall and the rear edge of the base; an upstanding tongue formed integrally with the front flange of the base having a normal tendency to spring inwardly and provided with a seat; a projection formed on the front of the cover to enter the seat when the cover is closed; said base having a central raised portion near the rear edge and provided with a central opening; a post having a reduced lower end seated in the 115 opening; a nut threaded on said lower end beneath the raised portion to rigidly hold the post for filing the blanks and permitting same to be swung laterally; and a retaining nut threaded on the upper end of the post. 120

In testimony that I claim the foregoing as my own, I have hereto affixed my signature.

JOSEPH F. BARTOSH.
